UNITED STATES PATENT OFFICE.

JOSEPH HOYLMAN, OF COALTON, WEST VIRGINIA, ASSIGNOR OF ONE-HALF TO H. R. JONES, OF COALTON, WEST VIRGINIA.

ATTACHMENT FOR TROLLEY-WIRE HANGERS

1,196,781.

Specification of Letters Patent.

Patented Sept. 5, 1916.

Application filed November 9, 1915. Serial No. 60,497.

To all whom it may concern:

Be it known that I, JOSEPH HOYLMAN, a citizen of the United States, residing at Coalton, in the county of Randolph and State of West Virginia, have invented certain new and useful Improvements in Attachments for Trolley-Wire Hangers; and I do hereby declare the following to be a full, clear, and exact description of the invention, such as will enable others skilled in the art to which it appertains to make and use the same.

My invention relates to new and useful improvements in attachments for trolley wire hangers and more particularly to that class used in mines or other places where the suspended wires are in position to come in contact with a person or animal, and my object is to provide non-conducting guards and position the same on opposite sides of the wire to form a guard therefor.

A further object is to provide means for supporting the guards. And a further object is to so construct the device that it can be applied to use in connection with wire supports of various kinds.

Other objects and advantages will be hereinafter set forth and more particularly pointed out in the accompanying specification.

In the accompanying drawings which are made a part of this application, Figure 1 is an elevation of the guard showing one manner of attaching the same to the wire hanger. Fig. 2 is a bottom plan view thereof. Fig. 3 is a sectional view transversely through the guard support. Fig. 4 is an elevation showing a different means of attaching the support to the hanger, and Fig. 5 is a similar view of a still different means of attaching the guard support to the hanger.

Referring to the drawings in which similar reference numerals designate corresponding parts throughout the several views, 1 indicates a hanger which may be of the usual or any preferred construction and designed to receive at its lower end a clamp 2 which clamp engages a trolley wire 3 and suspends the wire from a ceiling or roof of a mine or other suitable place, and in order to protect the wire and prevent any one from coming in contact therewith whereby they would be injured from the current passing through the wire, I provide

guards 4 which are placed on opposite sides of the wire a distance therefrom and extending above and below the wire, said guards being constructed of any suitable insulating material, preferably wood.

In order to retain the guards in proper position and hold the same spaced from the wire 3, a support 5 is provided, said support terminating in downwardly extending arms 6 at each end to which the guards 4 are attached by means of bolts 7 or in any suitable manner.

The supports 5 may be attached to any suitable part of the hanger and as shown in Figs. 1, 2 and 3, it is attached to the clamp 2 and properly insulated therefrom, while in Fig. 4 of the drawings the support 8 is formed integral with the bell 9 of the hanger, said bell being likewise insulated from the wire 3. Where the trolley system is already installed, that form of support 10 shown in Fig. 5 may be used which is introduced around the hanger 1 between the bell 9 and the roof of the mine or other object to which the hangers are attached, this form of hanger being also insulated from the hanger in any suitable manner to prevent the current in the wire from passing into the support.

The guards 4 are constructed of sufficient rigidity and placed a sufficient distance from the trolley as to prevent the guards from coming in contact with the wire, thereby obviating any possibility of the current passing through the guard should the guard be wet or damp.

It will likewise be seen that this device can be very cheaply constructed and readily installed either by forming the same in connection with the parts of the hanger before the hanger is installed or attaching the same to the hanger after installation as shown in Fig. 5 and as the guards extend longitudinally of the trolley wire they will efficiently protect the wire and prevent anyone coming in contact therewith. And it will likewise be seen that in view of the distance between the trolley wire and guards, the trolleys will readily pass along the wire without coming in contact with the guards or in any manner disturbing the same.

Having thus fully described my invention what I claim as new and desire to secure by Letters Patent of the United States, is:—

An attachment for trolley wires to pro-

vide safety guards therefor, comprising supports adapted to be connected with the hangers of said wires, said supports comprising horizontal members extending laterally therefrom, rigid integral arms depending downwardly from the ends of said horizontal members and extending for a distance below the horizontal plane of the trolley wires, and provided with horizontally spaced pairs of apertures through their lower end portions, guards of non-conducting material extending longitudinally of the wires on opposite sides thereof in spaced relation thereto and projecting above and below the same, said guards having squared ends adapted to lie in abutting re-

lation to each other at the inner sides of said depending arms at substantially the transverse centers thereof and bolts projecting through the apertures of the lower end portions of said rigid depending arms and the end portions of said guards for removably and independently securing said guards to said depending arms. 20

In testimony whereof I have signed my name to this specification in the presence of two subscribing witnesses.

JOSEPH HOYLMAN.
